WRENCH ADAPTER

Gilbert C. Whitney, New York, N. Y.

Application December 1, 1939, Serial No. 307,021

5 Claims. (Cl. 81—58)

This invention relates to adapters for wrenches and is primarily of advantage for turning members such, for example, as nuts or bolts so located that the space within which the wrench may be turned is small with the result that the wrench 5 has a limited angle of swing.

One object of the invention is to provide for a turning of the member to be turned by an angle of swing of the wrench and the wrench reengaged 10 for its next turning movement within that angle of swing, which angle of swing is less than the angle subtended by the individual operative faces of the adapter.

A second object of the invention is to provide 15 two operative driving sections or heads on the adapter separated by a pilot or race section by which latter means the wrench may be guided between the two operative sections in its change of position both radially and longitudinally in 20 moving from one operative section or head to the other.

Other objects of the invention will be apparent 25 as this description proceeds.

In ordinary practice adapters are employed in 30 connection with sockets which latter at their bottoms fit over the members to be turned. These sockets at their bottoms are provided with various interior shapes and sizes to fit the members to be turned. At the top the sockets are formed 35 with a suitable opening commonly of square or hexagonal cross-section into which the adapters of like cross-section at the bottom are inserted and removably attached. The adapter has its top formed for engagement with the wrench 40 block or head and is commonly of square or hexagonal cross-section. It is convenient to use 45 sockets of this character with the adapter of this invention, although, as is obvious, if desired the adapter may be formed and shaped at the bottom to engage directly with the member to be turned.

Box wrenches are most commonly employed 50 with adapters although any suitable type of wrench with an open block may be used. Reference being had more particularly to box wrenches, 55 the terminology commonly employed in the trade for defining the number of operative faces is by reference to the boundary lines between adjacent faces which lie in what may be termed the outer circumferential line of the block interior. 60 These are referred to as "points." Reference being had, for example, to the double hexagonal 65 and box wrench specifically illustrated herein and later to be more fully described, there are twenty- 70 four vertical faces, each face being bounded and

defined by two vertical lines, one of which lies in what I have termed the outer circumference of the block interior and the other in what may be termed the inner circumference thereof. This wrench, defined by the boundary lines which lie 5 in the said outer circumference, thereof, is a twelve "point" box wrench. Again, for example, in a box wrench with a single hexagonal block interior the vertical boundary lines of the respective faces all lie in the same circumferential 10 line of the block interior. Such a wrench is a six "point" box wrench. It is preferred, though not essential, to employ a box wrench with the adapter of this invention and that wrench will be 15 specified by its "points."

In the drawing hereof I have illustrated two forms of adapters, both for use in connection with suitable sockets. Both forms have hexagonal driving sections or heads. One form is particularly adapted for use in connection with a double 20 hexagonal twelve point box wrench which is illustrated, and the other form with a single hexagonal six point box wrench which is not specifically shown. The two forms shown, it should be 25 understood, are selected for illustrative purposes and should not at all be considered as limitative upon the scope of my invention.

In the drawing, Figure 1 is an elevation of the adapter mounted in a socket and having its co-operating wrench partly lowered toward full 30 operative position on the upper driving section or head, the position of the wrench on the pilot or race section being indicated in broken lines, the wrench being broken away in its handle;

Fig. 2 is a top plan on an enlarged scale of the 35 wrench and adapter of Fig. 1 with the socket omitted, the wrench being shown as engaging the upper driving section or head of the adapter;

Fig. 3 is a top plan on the scale of Fig. 2 of the 40 wrench and adapter of Fig. 1 with the lower driving section or head of the adapter and the socket omitted, the wrench being shown as engaging the upper driving section or head of the 45 adapter;

Fig. 4 is a top plan on the scale of Fig. 2 of the 50 wrench and adapter of Fig. 1, the adapter being shown in cross-section through the pilot or race section and the socket being omitted, the wrench being shown in position upon the pilot or race section;

Fig. 5 is a top plan on the scale of Fig. 2 of the 55 wrench and adapter of Fig. 1, the adapter being shown in cross-section through the pilot or race section and the socket omitted as in Fig. 4, the

wrench being shown in engagement with the lower driving section or head of the adapter;

Fig. 6 is a top plan on the scale of Fig. 2 of the wrench and adapter of Fig. 1, the socket being omitted, the wrench being shown in engagement with the lower driving section or head of the adapter;

Fig. 7 is an elevation of the adapter of Fig. 1; and

10 Fig. 8 is an elevation of the second form of the adapter heretofore referred to.

Because of the multiplicity of lines required for a complete showing and the confusion likely to result therefrom, in Figs. 2, 3, 5, and 6 the 15 operative faces of the wrench block or head which are in engagement with the faces of the upper and lower driving sections or heads of the adapter, together with the said faces of the adapter are illustrated by single lines. The 20 double hexagonal outline of the block or head interior of the wrench is, however, illustrated in full lines in Fig. 4.

Reference being had first to the adapter illustrated in Figs. 1 to 7, inclusive, the adapter 10 25 has an upper hexagonal driving section or head 11, a cylindrical pilot or race section 12, and a lower hexagonal driving section or head 13, the latter being extended downwardly for operative engagement with the interior of a socket 30 14, where it is removably held by a spring pressed ball 15, stops not shown being provided in conventional fashion for determining the proper vertical position of the adapter in the socket whereby the lower driving section or head 13 35 extends above the socket a distance substantially equal to the lengthwise dimension of the upper driving section or head 11.

The hexagonal driving sections or heads 11 and 13, respectively, are of substantially identical 40 cross-section. The diameter of the cylindrical pilot or race section 12 is substantially equal to the cross-sectional distance between the oppositely disposed working faces of the driving sections or heads, and its lengthwise dimension is 45 substantially equal to that of the upper driving section or head 11. The upper driving section or head 11, the pilot or race section 12 and the lower driving section or head 13 are in line with each other, but the working faces of the 50 upper driving section or head are radially displaced at a 15° angle from the corresponding working faces of the lower driving section or head.

The wrench illustrated for use with the adapter 10 is a double hexagon, twelve point box wrench 20 having an offset handle 21 and a block or head 22.

The head 25 broken away, shown in the lower part of the socket 14 is illustrative of the member to be turned by the combined wrench, adapter and socket shown.

The operation of the wrench 20, adapter 10, and socket 14 of Fig. 1 is as follows:

The socket 14 with the adapter 10 in position 65 therein is placed over the head 25 of the member to be turned. The wrench 20 is then placed in operative position on the upper driving section or head 11 as shown, for example, in Fig. 2. Assuming that it is desired to rotate the head 70 25 in clockwise direction the wrench handle is moved from the position of Fig. 2 through an arc of 15° to the position of Fig. 3. From the position of Fig. 3 the wrench is lowered out of engagement with the upper driving section or 75 head 11 onto the pilot or race section 12 as

shown in Fig. 4. From the position of Fig. 4 the wrench is rotated about the pilot or race section 12 counter-clockwise through an arc of 15° to the position of Fig. 5. The wrench will then be in position to slide vertically into engagement with the lower driving section or head 13 to which it is moved. The wrench then in engagement with the lower driving section or head 13 is rotated clockwise through an angle of 15° to the position of Fig. 6. Through this 10 sequence of operations the adapter 10, socket 14, and head 25 have been rotated through an angle of 30°.

From the position of Fig. 6 with the wrench in engagement with the lower driving section 15 or head 13 the wrench is moved upwardly to the pilot or race section 12 and there rotated counter-clockwise through an angle of 15° as shown in Fig. 5 in which position it is moved upwardly into engagement with the upper driving section 20 or head as illustrated in Fig. 2 in readiness for repetition of the sequence of operations of Figs. 2 to 6, inclusive, just described.

Reference now being had to the form of adapter illustrated in Fig. 8, that adapter 10' is identical in all respects with the adapter 10 of Fig. 7 except in the angle by which the working faces on the upper driving section or head are radially displaced in respect to the corresponding working faces on the lower driving section 30 or head. For this reason the reference numerals of the adapter of Fig. 7 with primes (') are applied to the corresponding parts of the adapter of Fig. 8, without further description. The working faces of the upper driving section or head 11' of Fig. 8 are illustrated as radially displaced at an angle of 30° from the corresponding working faces of the lower driving section or head 13'.

As indicated in the preamble hereof, a single 40 hexagon six point wrench is preferably to be employed with the adapter illustrated in Fig. 8. With such a wrench the sequence of operations in rotating the member to be turned is identical with that above described respecting the 45 adapter of Figs. 1 to 7, except that the angle of swing of the wrench is through an arc of 30° instead of 15°.

To understand the operation of the two forms of adapter illustrated respectively in Figs. 7 and 50 8 in respect to current practice, the following should be noted.

With twelve point sockets or double hexagon twelve point box wrenches commonly employed on hexagonal members to be turned, it is possible to operate in a minimum angle of swing of 30° only by replacing the socket or box wrench on the member to be turned. Due to this the wear on the corners of the members to be turned is more than doubled soon causing them to become upset or sheared. This deformation of the member to be turned tends to be increased by the absence of active face cut away in the pocket or box wrench of the twelve point type. This wear and tear on the member to be turned is 65 practically eliminated by the use of the adapter of this invention because the socket is placed on the member to be turned but once. Such wear and tear is not transferred to the adapter of this invention because of the pilot or race section 70 interposed between the two driving sections or heads all of hardened material.

Where in current practice a single hexagon six point wrench is employed with a member to be turned having a hexagonal head, regardless 75

of the angle through which the member may be turned the wrench must be turned through an angle of 60° , in order to place the wrench in the next operating position, as against 30° possible with the adapter of Fig. 8.

Attempts have been made to overcome these difficulties in current practice, the most common of which is by embodying a ratchet in the wrench. The wrench, however, must be capable of exerting pressure for turning the adapter both in clockwise and counter-clockwise direction, and this requires a ratchet which may be locked for both directions or a ratchet which is removable and may be turned the other side up, as it were, when it is desired to exert pressure in the opposite direction from that for which the ratchet is set in the wrench. In addition to these comparatively expensive and poor mechanical expedients, the ratchet is bulky and occupies space in many instances not available. Applicant's invention avoids completely the employment of a ratchet.

While I have illustrated my invention as embodied in adapters having an even number of operative faces in its respective driving sections or heads it should be readily understood that this is not essential. The faces of the driving sections or heads should be uniform in the cross-section of the adapter and regularly placed thereon, the same number of working faces being employed in the upper and lower driving sections or heads.

The angle by which the corresponding faces of the upper driving section or head are radially displaced in respect to the corresponding working faces of the lower driving section or head as herein illustrated, is equal to one-half of the angle subtended by two consecutive points in the block or head of the wrench to be employed. This provides for a uniform angle of swing, which is preferred though not essential. It will be understood that the said angle of radial displacement will vary in accordance with the number of working faces on the upper and lower driving sections or heads of the adapter and the wrenches to be employed therewith, preferably in accordance with the limitation just set forth.

While I have illustrated a pilot or race section of cylindrical form it will be understood that this is not essential to the broad purposes of this invention. The form of the pilot or race section should be such as to permit both vertical and radial movement of the block or head of the wrench in its transposition from one driving section or head of the adapter to the other driving section or head thereof, and to pilot or guide the wrench to its respectively engaged operating position.

The foregoing detailed description has been given for clearness of understanding and no undue limitations on the scope of this invention should be inferred therefrom.

I claim:

1. The combination of a box wrench, an adapter, and a socket removably attached to the adapter in non-rotatable relation thereto, the box wrench being provided with a block or head formed with a plurality of oppositely disposed working faces for engagement with the adapter; the adapter being formed with an upper driving section or head and a lower driving section or head separated by a pilot or race section, the upper driving section or head, the pilot or race section and the lower driving section or head being in line with each other and with the

socket, the upper driving section or head and the lower driving section or head being of substantially identical cross-section and being each provided with the same number of oppositely placed uniform working faces disposed longitudinally of the adapter, the pilot or race section being substantially cylindrical and of such length and diameter as to permit the block or head of the wrench to rotate freely about the pilot or race section, the working faces on the upper driving section or head being radially displaced at an angle to the corresponding working faces of the lower driving section or head equal to one-half the angle subtended by two consecutive points in the wrench block or head. 15

2. The combination of a wrench and an adapter; the wrench being provided with a block or head formed with a plurality of working faces for engagement with the adapter; the adapter being provided at the bottom with means for engaging the member to be turned and being formed with an upper driving section or head and a lower driving section or head separated by a pilot or race section, the upper driving section or head, the pilot or race section and the lower driving section or head being in line with each other, the upper driving section or head and the lower driving section or head being of substantially identical cross-section and being each provided with the same number of uniform working faces disposed longitudinally of the adapter, the pilot or race section being so constructed and of such dimensions as to permit the block or head of the wrench to rotate freely thereabout, the working faces of the upper driving section or head being radially displaced at an angle to the corresponding working faces of the lower driving section or head equal to one-half the angle subtended by two consecutive points in the wrench block or head. 35

3. A wrench adapter comprising an upper driving section or head, a lower driving section or head, each for engagement with the block or head of the wrench, a cylindrical pilot or race section between the upper driving section or head and the lower driving section or head about which the block or head of the wrench may turn, the upper driving section or head, the pilot or race section, and the lower driving section or head being in line with each other, the upper driving section or head and the lower driving section or head being of substantially identical cross-section and being each provided with the same number of regularly placed uniform working faces disposed longitudinally of the adapter, 45 the diameter of the cylindrical pilot or race section being substantially equal to the transverse distance between the regularly disposed working faces of the driving sections or heads, the working faces of the upper driving section or head being radially displaced at an angle to the corresponding working faces of the lower driving section or head. 55

4. A wrench adapter comprising an upper hexagonal driving section or head, a lower hexagonal driving section or head, each for engagement with the block or head of the wrench, the said driving sections or heads being of substantially identical cross-section, a cylindrical pilot or race section between the upper driving section or head and the lower driving section or head about which the block or head of the wrench may turn, the upper driving section or head, the pilot or race section, and the lower driving section or head being in line with each other, 70 75

the diameter of the cylindrical pilot or race section being substantially equal to the distance between the oppositely disposed working faces of the driving sections or heads, the working faces of the upper driving section or head being radially displaced at a 15° angle from the corresponding working faces of the lower driving section or head.

5. A wrench adapter comprising an upper hexagonal driving section or head, a lower hexagonal driving section or head, each for engagement with the block or head of the wrench, the said driving sections or heads being of substantially identical cross-section, a cylindrical pilot or race section between the upper driving sec-

tion or head and the lower driving section or head about which the block or head of the wrench may turn, the upper driving section or head, the pilot or race section, and the lower driving section or head being in line with each other, the diameter of the cylindrical pilot or race section being substantially equal to the distance between the oppositely disposed working faces of the driving sections or heads, the working faces of the upper driving section or head being radially displaced at a 30° angle from the corresponding working faces of the lower driving section or head.

GILBERT C. WHITNEY.
